F. S. LORENZ,
CORRESPONDENCE KIT FOR TRAVELERS,
FILED JULY 13, 1921.

By

Inventor
Frances S. Lorenz
Frances S. Lorenz

Attorney

UNITED STATES PATENT OFFICE.

FRANCES SIBLEY LORENZ, OF AUGUSTA, GEORGIA.

CORRESPONDENCE KIT FOR TRAVELERS.

Application filed July 13, 1921. Serial No. 484,302.

To all whom it may concern:

Be it known that I, FRANCES SIBLEY LORENZ, a citizen of the United States, residing at Augusta, in the county of Richmond and State of Georgia, have invented 5 certain new and useful Improvements in Correspondence Kits for Travelers, of which the following is a specification.

My said invention relates to an improved 10 correspondence kit for travelers and it is an object thereof to provide an improved container to hold letter paper and a pencil or other instrumentality for writing on the same.

15 A further object is to provide a device of the character described which shall be simple and inexpensive and which may be discarded after the paper has been used up.

Referring to the accompanying drawings 20 which are made a part hereof and on which similar reference characters indicate similar parts,

Figure 1 is a perspective of the device in open position, certain of the dotted lines 25 indicating the closed position of the parts, and

Figure 2 is a section of the same in closed position.

In the drawings 10 indicates the bottom 30 of the package which when the package is on display forms the face member and may have on its outer surface inscriptions of various kinds. I have proposed, for example, to place thereon a picture showing pine trees on a hillside with a rising moon in rear thereof and a legend such as "Bon voyage" or "Bon chance", thereon. Side members 11 and 12 extend from member 10 and are adapted to fold over and enclose 35 the contents of the package. The material of the cover is bent so as to form narrow strips 13 which correspond to the height of the material in the package when full. At one end of the package is a narrow strip 40 14 and a wider part 15 which folds over the paper to hold it in place.

At the other end of the package is a folded portion of material comprising a narrow strip 15, a wider strip 17, a second 45 narrow strip 18 and a second wider strip 19 all of which together serve to enclose a pencil 20. These parts fold over and enclose a pencil and both the pencil holding parts and the paper retaining parts 14 and

15 at the other end are preferably made to 55 fold under the side wings 11 and 12.

I have shown the pencil as being of ordinary flat form with an enclosing metallic casing 21 but it will be evident that the form of the pencil may vary and the form 60 of the enclosing strip will also vary correspondingly. The dotted lines in Figure 2 show the enclosing strip in open position.

Preferably the holder is filled with paper having lines of perforations extending down 65 each side and across each end as indicated at 22. The narrow strip between the lines of perforations and the edge of the paper is covered with dry mucilage. A letter may be written on the inside of the sheet which 70 is then folded along the rear edge at 23, after which the mucilage is dampened and the edges of the paper caused to adhere. The address may then be written on the outside, a stamp affixed and the letter 75 mailed as an ordinary letter.

It will be evident that various changes may be made in the device without departing from the spirit of the invention or the scope of the appended claims. The kit is 80 particularly adapted for use in situations where the ordinary facilities for correspondence are not available as on trains and ships and where it is desirable to provide everything necessary in the smallest possible 85 compass. While my device is described as intended to contain letter paper it is obviously adapted to hold post cards, visiting cards and other similar devices.

Having thus fully described my said invention, what I claim as new and desire to secure by Letters Patent, is:

1. In a correspondence kit, a container formed of a single sheet of heavy paper, the container having a back, side and end 95 pieces folding against the back and forming means for holding letter paper, one of said end pieces being adapted to fold entirely around and hold a pencil, substantially as set forth.

2. A correspondence kit comprising a single sheet of material folded to form separate compartments for a pencil and letter paper and entirely enclose the same, substantially as set forth.

3. A correspondence kit having a back, an end piece and side pieces folded thereover to form a pocket for letter paper, and an-

100

105

other end piece folding under the side wings to form a pocket for a pencil, said end piece also forming a closure for the upper end of the pocket, substantially as set forth.

4. A correspondence kit formed of a single sheet of paper having permanent creases at the sides and ends along which the same may be folded to provide separate 10 enclosed pockets, respectively for letter paper, and for means for writing thereon, substantially as set forth.

5. A correspondence kit having a back, side portions folding against the back to

form a container for writing paper, and a 15 pencil pocket at one end of said container, said pocket serving to limit the movement of the writing paper, substantially as set forth.

In witness whereof, I have hereunto set 20 my hand and seal at Augusta, Georgia, this 11th day of July, A. D. nineteen hundred and twenty-one.

FRANCES SIBLEY LORENZ. [L.S.]
